UNITED STATES PATENT OFFICE

2,000,585

ELECTROMAGNETIC IMPULSE CLOCK

Jean Fink, Waltham, Mass., assignor to Waltham Watch Company, Waltham, Mass., a corporation of Massachusetts

Application August 23, 1932, Serial No. 630,628

13 Claims.

(Cl. 58—41)

This invention relates to time pieces of the type in which a driving spring is periodically rewound by magnetic impulses effected by closing the circuit of an electro-magnet whenever a predetermined proportion of the energy of the spring has been expended. The object of the invention has been to furnish a clock of this character possessing the capability of long life with minimum deterioration through many operations of its circuit controlling switch, and the nature of which lends itself to design in a large variety of different sizes and capacity for operation by currents of widely varying voltages. That is, more specifically, my aim has been to provide a clock suitable for use in automobiles, for instance, operable by the low voltage current of the storage battery of such an automobile, and capable of functioning without derangement notwithstanding the shocks and vibrations to which it is subjected when carried by an automobile; while the same design, with appropriate variations, may be embodied in mantel or wall clocks and the like, operable by electric lighting currents and other currents of comparably high, or higher, voltages, whether direct or alternating. Another object has been to furnish a clock which, with a minimum of change, may be connected in either an insulated electric circuit or in a grounded circuit.

While primarily designed for the purposes above stated, the principles and essentials of the new invention are not limited to use in a clock only, but are adapted for driving other mechanisms also.

The new characteristics of the invention include, among other things, the use of an enclosed gravity switch movable angularly by and with the armature of an electro-magnet, the use of the same spring to serve both as a leading in conductor for the switch and as the main driving spring of the time piece, and means including replaceable switch carriers for adapting the same time piece for use either in an insulated circuit or a grounded circuit.

In the drawing,—

Fig. 1 is a rear elevation of the time piece showing particularly the electrical equipment;

Fig. 2 is a horizontal section on line 2—2 of Fig. 1;

Fig. 3 is a partial rear elevation and partial section on line 3—3 of Fig. 2;

Fig. 4 is a section on line 4—4 of Fig. 2;

Fig. 5 is a section and rear elevation on the

plane of line 5—5 of Fig. 2, shown on an enlarged scale;

Fig. 6 is a cross section on line 6—6 of Fig. 5;

Fig. 7 is an elevation and partial section of the switch carrier shown in Figs. 1 and 2;

Fig. 8 is a cross section of the same taken on line 8—8 of Fig. 7;

Fig. 9 is a view similar to Fig. 1 showing the arrangement of the apparatus adapted for use in a grounded electrical circuit;

Figs. 10 and 11 are sectional views of the switch carrier taken on line 10—10 and 11—11 respectively of Fig. 9;

Fig. 12 is a perspective view of the associated disk and pinion which drives the clock train through the medium of a coupling spring;

Fig. 13 is an elevation of the coupling spring and the ratchet wheel which applies tension thereto under impulsion by the main spring.

Fig. 14 is a view similar to Fig. 9 showing an added means for obtaining quick closing and opening of the switch;

Fig. 15 is a similar view of the switch showing it in open circuit position;

Fig. 16 is an elevation of the connector between the switch carrier of Fig. 14 and the staff of the armature.

Like reference characters designate the same parts wherever they occur in all the figures.

The electrical and magnetic equipment of my improved clock comprises an electromagnet having pole pieces 11 and 12, a wire coil 13, an armature 14, a switch carrier 15, and a gravity switch 16. The pole pieces are secured to a holder plate 17 by posts 18, 18, and 19, 19, to which nuts are applied. A laminated core 20 passing through the magnet coil or winding is secured by the posts 18, 18 and the nuts thereon. A bridge 21 of non-magnetic material passes across the gap between the magnet poles at the opposite side of the latter from the plate 17, being positioned by the posts 19, 19, and secured by nuts on said posts. This bridge and the plate 17 provide bearings for a staff 22 to which the armature 14 is secured. Said staff also protrudes beyond the bridge and supports the switch carrier 15.

Preferably the magnet poles have concave faces opposite to each other and equidistant from the staff 22, and the armature is a massive bar having a length nearly as great as the distance between these opposed faces, so that it may rotate between them with a minimum air gap, but has a substantially less width.

The switch carrier 15 is a block of insulating

material preferably, although not necessarily, of cylindrical shape and of substantially the same diameter as the longer dimension of the armature. It may, however, be of any size and shape which enables it to occupy, and freely rotate in, the area between the coil 13, posts 19, 19, and the nearer part of the circumference of plate 17. It is secured to the staff 22 by a set screw 23 threaded through the base of a thimble 24 which is embedded in one side of the carrier.

The switch 16 in this embodiment is a mercury switch consisting of a glass tube containing a globule 25 of mercury, and in one end of which are sealed the ends of wires 26 and 27 which constitute the terminals of the switch. This tube is sunk into the carrier 15 from the end face thereof at one side of the pivot axis or staff and with its longer dimension tangential to an arc concentric with such axis so that, when the carrier is mounted with its axis horizontal, and is rotated, the mercury globule will roll or flow by gravity from one end to the other of the tube.

With the clock organized for connection in an insulated electric circuit, two spiral springs 28 and 29 are provided, secured respectively to posts 30 and 31 which are mounted on the plate 17 and project rearwardly therefrom. The posts may be insulated from the plate, or the springs insulated from the posts by any suitable means known in the art; the important fact is that both are insulated from the plate and other conductive parts of the clock structure, and from each other. Spring 28 extends across the back or outer side of the switch carrier and is connected with a pin 32 which in turn is connected with the switch terminal 26 by a conductor 33. Spring 29 crosses the inner or front side of the switch carrier and is connected with a pin 34 which in turn is coupled electrically by a conductor 35 (Fig. 2) with the switch terminal 27. These pins are mounted in the switch carrier in any manner suitable to hold them with the rigidity necessary for performing their mechanical functions later described; and the conductors 33 and 35 are led to them from the switch terminals in any convenient manner, preferably being led and embedded in channels cut or pierced in the substance of the carrier. As this substance is of insulating material (at least as to that part of the carrier which holds the pins and conductors), the two pins and their conductors are insulated from each other.

One of the springs, as 29, is connected by a conductor 36 with one terminal of the magnet coil. The other spring and the other terminal of the coil are connected by conductors 37 and 38 to the opposite sides of a source of current, here represented conventionally as a battery 39.

The springs 28 and 29 are designed to serve also as main springs for driving the clock movement. They are therefore coiled in a spiral of several convolutions and are made of a substance, size and mass suitable for this purpose as well as for the purpose of carrying whatever current may be needed to energize the magnet. Alloys of copper, classed as bronzes, are known in the art which have ample hardness and resilience, as well as conductivity, for these purposes; and I prefer to make these springs of such an alloy. However, steel may be used provided the springs are made with suf-

ficient sectional area to carry the current. They are also put under tension, or partially wound up before the clock is put into service; which may be done by rotating the holder 15 on the staff before the set screw 23 is tightened up to clamp it. When set up ready for service, the parts are so placed that the springs exert tension counterclockwise on the armature 14, tending to hold it in a position crosswise of the lines of magnetic force, where it is arrested by a pin 44, which is carried by the armature, engaging one end of an arcuate slot 45 in the plate 17; and the switch is then in the position shown in Fig. 1 with its end which contains the terminal contacts enough lower than its other end to insure location of the mercury globule in that end and in contact with the switch terminals.

To equip the clock for grounded circuit use, the spring 28 is removed and the switch contact 26 is grounded on the framework. This change 20 may be most easily made by substituting for the switch holder 15, an equivalent switch holder 15a which is identical with it except in that the contact 26 is coupled by a conductor 46 with the metal socket 24 wherein set screw 25 23 is seated; and the circuit connection is continued through such set screw and the staff 22 to the frame of the clock. The contact 26 is connected by conductor 33 with pin 34a which projects from the forward side of the switch 30 carrier for connection with spring 29 and passes through the substance of the carrier far enough for connection with said conductor. This arrangement is particularly suited to clocks designed for use in automobiles, where the frame 35 of the clock movement, and one pole of the storage battery, are grounded on the frame of the automobile, the other pole of the battery being coupled by an insulated conductor with the magnet coil 13, and the latter and spring 40 29 being also insulated from the frame. The clock movement consists of the usual gear train and balance escapement, the members of which are mounted between a pillar or front plate 41 and a back plate 48, and/or a bridge or bridges 45 of any suitable design. That is, the clock movement may be like any spring driven movement, or of any other suitable design, except that the usual main spring of such clock is omitted. Energy for driving the movement is furnished by the springs 28 and 29, or the single spring 29 when only one is used, transmitted from the armature 14 by the pin 44, previously mentioned, which projects through the slot 45 (which is concentric with staff 22) in the plate 17, and a registered slot in plate 48 to connection with a driving member 49 for the clock movement. This connection is a permanent one.

Such driving member is here made as a disk rotatable about a staff 50 mounted in the plates 47 and 48 in alinement with staff 22. It drives through a one-way clutch consisting of a ratchet wheel 51, also rotatable about the same staff, and a pawl 52 connected to the disk by a pivot stud 53 and pressed upon by a spring 54, which also is connected to the disk by a screw 55. A coupling spring 56 for continuing the driving effort while the mainspring is being wound, made as a spiral of several convolutions surrounding staff 50, is contained in a recess in the ratchet wheel and connected at one end thereto by means of a pin 57, and at the other end to a pin 57a which projects into the recess from a disk 58, which is so mounted on the staff as to overlie said recess. This spring is made of 75

sufficient length to drive the clock for an extended time, for instance half an hour or more, to avoid necessity of resetting the clock if the current supply should fail temporarily. A pinion 58 is made fast to staff 50 and drives the center wheel 68 of the clock time train through an idle pinion 61 which turns about a pivot stud anchored in the plate 48.

It will now be apparent that when the magnet is energized, by closing of the switch when the armature occupies a position wherein its major dimension is transverse to the magnetic lines of force, the armature is given a sudden impulse in clockwise rotation (with respect to the drawing) which is powerful enough to give it momentum sufficient to carry it to the limit of movement imposed by structural parts of the device; such movement being in the construction shown nearly 180°. Thus the driving pawl 52 is carried backward around the rim of ratchet wheel 51, which is prevented from turning with it, by a holding pawl 62 pivoted to a stud 63 and pressed toward the ratchet by a spring 64; said pivot stud and spring being secured to plate 48.

Switch holder 15 is turned at the same time, and as soon as the circuit is broken by the mercury globule falling away from the terminal contacts, the magnetic flux ceases, leaving the armature free to be carried by its momentum beyond the position where it receives the greatest concentration of magnetic lines of force. At the same time the springs 28 and 29, or spring 28 when 29 is omitted, are put under increased tension which, together with the initial tension, is amply sufficient to drive the movement. When, in the course of the rotation imparted by such spring or springs (occurring in the counter-clockwise direction with respect to the drawing) the pin 44 nearly reaches the end of slot 45, and the armature is brought crosswise to the field of the magnet, the switch arrives in position for completing the circuit; and the previous action is repeated.

It is desirable, when the clock is used in an automobile, to prevent the jolting and vibration of the automobile from throwing the mercury globule against the terminal contacts prematurely, as it might when the switch has nearly attained a horizontal position but has not turned far enough for the globule to pass by gravity into circuit closing position. To prevent this I provide an obstruction or baffle 65 in the casing of the switch (which is most conveniently made by indenting the side of the glass tube when softened by heat) so located and designed as to hinder displacement of the globule by jolting, while permitting its displacement by gravity when the switch is in the proper position. But this, while a desirable feature, is not essential; and it is unnecessary in connection with a clock provided for use where it is not subjected to any considerable vibration.

The fact that the switch is mounted off center from its axis of revolution is a useful feature, as it causes the momentum of the globule, imparted by its rapid revolution under the magnetic impulse, to carry it forcibly away from the terminal contacts and insure opening of the circuit when the armature is arrested at the end of its swing. Such arrest occurs in this design when the pin 44 brings up against the end of pawl 62, but it may equally well be caused by the end of slot 45.

A further means for effecting sudden opening

and closing of the circuit, which may be used with the means just described, or alternatively thereto, is shown in Figs. 14-16. It comprises mounting the switch carrier with capacity for angular motion independently of the armature, impelling it by the armature with provision for lost motion, and giving it an increment of angular movement, suddenly applied, when the armature nears the end of its swing in each direction.

In the embodiment illustrated, which is applied to the grounded circuit arrangement of the electrical apparatus, the switch carrier 15 is mounted loosely on the armature staff 22, and a plate or disk 66 is mounted fixedly on the staff. One of the springs 28 or 29, or its equivalent, here designated as 28a, is coupled to the plate 66, or to the staff so as to have the same mechanical functions previously described. It does not, however, have any electrical function. Two or more springs may be so used if desired.

The switch carrier is provided with a pin 67 which projects into a notch 68 in the disk 66, serving as a coupler by which the disk propels the switch carrier in both directions, and providing for an angular lost motion of any desired amount. I have found in practice that an angle of 15° or 20° is satisfactory, but do not limit my invention narrowly in this respect. A helical spring 69 is anchored to the post 19 and coupled to the switch carrier by a pin 70 so located that when the switch is in circuit closing position (Fig. 14) the pull of the spring is exerted at one side of the axis of revolution tending to turn the switch further in the direction traversed when arriving in that position; and when the switch and armature are near the opposite limit of oscillation (Fig. 15) the pull of the spring is at the opposite side of the axis and exerts turning movement in the opposite direction. In the course of the rotation of the armature in either direction the pin 70 crosses the dead point and the direction of turning moment applied by spring 69 on the switch carrier is reversed.

The effect of the spring 28a or its equivalent, like that of the springs 28 and 29, is to rotate the staff in counter-clockwise rotation, turning the disk 66 from the position shown in Fig. 15 to that shown in Figs. 14 and 16, and the disk then impels the switch carrier by the boundary 71 of notch 68 acting on pin 67. This pin, and also pin 70, are angularly so related to the switch or circuit closer that when the latter is thus brought to a horizontal position, or nearly so, and while the mercury globule is still in the end of the tube remote from the terminal contacts, the pin 70 is brought past the dead point, whereupon the spring instantly advances the switch carrier through the angle of lost motion, which is made great enough to insure gravity displacement of the mercury globule into circuit closing position. Movement of the mercury is also expedited by its momentum and the sudden arrest of the switch carrier when pin 67 brings up against the opposite boundary 72 of the notch. The disk 66, being then turned in clockwise rotation by the magnet armature, propels the switch carrier by means of the bounding edge 72 until the pin 70 passes the dead point again, and spring 69 then suddenly gives the switch carrier its incremental angle of lost motion in the clockwise direction. Sudden arrest of the switch carrier again occurs when the pin 67 reaches the boundary 71; and the inertia effects resulting therefrom are cumulative of those

due to arrest of the armature. Thus closing and opening of the circuit are positively insured, and possibility of any of the mercury remaining in bridging connection across the switch terminals is definitely excluded. The mercury is forcibly propelled over any obstacle, such as the baffle 65, which may be provided to prevent premature closing of the circuit due to jolting of the clock.

10 It will be understood that the directions indicated in the foregoing description as clockwise and counter-clockwise have reference to the present illustration, which shows the electrical equipment in rear elevation, and are not 15 to be confused with the actual direction of rotation of the hands of the clock with which this motive mechanism is used.

In the arrangement just described the spring 69 forms part of the electric circuit, being in 20 circuit with the conductor 36 and with pin 70, which in turn is coupled by a conductor 73 with one of the switch terminals, the other terminal being connected by a conductor 74 with a metal bushing 75 in the switch carrier which surrounds 25 staff 22. When used in an insulated or non-grounded circuit, the connection 74 is led to an external contact on the switch carrier with which a stationary brush in the circuit makes contact. It is to be understood that the spring 30 69, while strong enough to give the incremental angular movement to the switch carrier herein described, may be much weaker than the main spring 28a, so as not to affect appreciably the functioning of the latter.

35 While I have described the member 66 as a disk, it will be understood that the outline and angular extent of this member is unimportant, provided only it subtends a large enough angle to provide abutments, as 71 and 72, between 40 which an impulse member, as the pin 67, on the switch carrier may play with the desired lost motion.

The use of a switch of the closed type is conducive to long life, for its tube or casing is 45 preferably filled with an inert gas, or it may be exhausted to a high degree of vacuum. Thus oxidation is entirely avoided and sparking largely eliminated. With low voltage currents the sparking is not serious enough to need any 50 consideration. It can be eliminated, or greatly diminished with currents of any voltage by including a condenser in the circuit. I have not shown such a condenser herein, because its use for that purpose is too well known to require 55 explanation.

With suitable selection and design of the electrical parts, according to principles well understood by electricians, clocks may be made according to the principles herein disclosed for use 60 with any voltage practicable for general use, and with either direct or alternating current. Such clocks, once properly regulated, will run without attention for very long periods and with only minute consumption of current.

65 It will be understood that while I have described a mercury switch as the preferred circuit closer in this combination, I am not limited to mercury as a mobile element of the closer, but may use a ball of solid conductive matter, or a liquid conductor other than mercury. Within certain aspects of the invention I may also use other types of gravity switch.

What I claim and desire to secure by Letters Patent is:

75 1. In a clock impeller of the character de-

scribed, an electromagnet having oppositely disposed poles, an armature rotatably mounted on an axis midway between said poles and having arms of greater length than width extending oppositely from the axis, a switch carrier secured to the staff of said armature to be carried and rotated thereby, a spiral spring coiled around the axis of said armature coupled at one end to said switch carrier and anchored at its opposite end, and an enclosed mercury switch or 10 circuit breaker mounted on said switch carrier to be tilted with rotation of the carrier and having separated terminal contacts at one end, one of said contacts being in electrical connection with the spring. 15

2. A clock impeller of the character described comprising a rotatably mounted magnet armature, a magnet having poles embracing said armature and adapted when energized to turn the latter from a position of greater reluctance 20 to another position of less reluctance with respect to the magnetic field, a switch carrier secured to the staff of said armature to be rotated thereby, a mercury switch comprising a closed tube containing a globule of mercury, closed 25 at both ends, mounted at one side of said staff with its length dimension tangential and having separated terminal contacts in one end, pins projecting from opposite faces of said switch carrier and each being separately in electrical 30 connection with one of said contacts, coil springs on opposite sides of the switch carrier surrounding said staff, each mechanically and electrically connected at one end to one of said pins and being mechanically anchored and electrically insulated at the other end, and electrical connections between said springs and the magnet winding and source of current respectively. 35

3. An electro magnetic impulse apparatus comprising an electro magnet having an oscillative armature, a spring tending to rotate said armature into a position of greater than minimum magnetic reluctance, a driven member impelled by said spring, a gravity circuit closer in the circuit of the electro magnet, a carrier for 45 said circuit closer rotatable about a horizontal axis, coupling means having an angular lost motion for rotating the switch carrier from the magnet armature, and means for rotating the switch carrier ahead of said impelling means 50 when it approaches circuit closing position.

4. In a clock of the character described, a revolvably mounted circuit closer having a mobile conductive element gravity impelled to circuit closing or circuit opening position according 55 to the position of the device about a substantially horizontal axis, an electromagnet having an armature mounted rotatably between the magnet poles with capacity for rotation through an angle of the order of 180°, means comprising 60 separated abutments connected for rotation by and with said armature and a projection from the circuit closer embraced between said abutments with provision for angular lost motion, a spring acting on the armature tending to 65 place it in a position of greater than minimum reluctance with respect to the field of the magnet, and means for suddenly advancing the circuit closer into circuit closing position when advanced near to such position by one of said 70 abutments under the impulsion of said spring.

5. The combination with an electromagnet, of an armature rotatably mounted between the poles of said magnet, yieldable impelling means acting on said armature and tending to return 75

- It to a position of greater than minimum reluctance with respect to the magnet field from a position of minimum reluctance with respect to such field, a member having angularly separated 5 abutments secured to said armature for angular movement by and with the same, a switch having a gravity impelled circuit closing element mounted to turn about a horizontal axis, a projection from said switch located with capacity 10 for lost motion between said abutments and adapted to be driven by one or the other of said abutments with rotation of the armature in respectively opposite directions, a spring coupled with said switch carrier at a point eccentric to 15 its axis of revolution so that the line of its force application is shifted from one side to the other of the axis of rotation as the switch carrier is advanced in either direction by one or the other of said abutments.
- 20 6. In an electromagnetically impelled clock, the combination of an electromagnet, a rotatable armature for said magnet, a spring connected to said armature and tending to place it in a position of greater than minimum reluctance to the magnetic field, a coupling between said armature and the clock movement for driving the latter, a switch carrier rotatably mounted co-axially with said armature and having a mercury switch in circuit with the magnet field, 25 the axis of the armature and switch being horizontal, separated abutments connected and movable with the armature, a projection from the switch carrier embraced by said abutments and having capacity for lost motion between them, 30 a spring coupled to said switch carrier to exert force at an eccentric point thereon toward the axis of the switch, but in a line extending past the axis on one side and then the other side thereof in the course of the armature-impelled 35 movement of said carrier.
- 40 7. An electromagnetic impulse motor comprising an armature, a switch carrier, and a driving member, all mounted oscillatively on the same axis and mechanically connected together, an electromagnet having poles embracing said armature, and the armature having a greater mass of magnetic material in one diameter than in any other diameter, an electric switch comprising an air excluding tube mounted on the 45 switch carrier containing separated contact terminals in one end and a mobile circuit closing body adapted to shift into and out of contact with said terminals as the switch carrier is rotated to one position or another, a driving 50 spring coiled around said axis, having a mechanical connection at one end with the before named oscillative members and a stationary anchorage at its opposite end and being under tension such that it tends to place the armature in a position where the diameter which contains 55 the greatest magnetic mass is transverse to the magnetic field, a stop co-operating with the spring to establish such position of the armature, the switch being then located with the end which contains said contact terminals lowermost, whereby the mobile body is caused by gravity to close the gap between them, and the armature being movable under magnetic impulse 60 from said position through an arc wide enough to tilt the switch so that the mobile body shifts out of engagement with said contact terminals, and a one way clutch operable by the driving member to transmit motion under the impulsion of said spring.
- 65

8. An electromagnetic impulse motor as set forth in claim 7 in which said spring is of electrically conductive material and is in electrical connection at one end with the field winding of the electromagnet and at its other end with one of said contact terminals, the other of said terminals being otherwise connected in the same circuit. 5

9. An electromagnetic impulse motor as set forth in claim 7 comprising two springs supported and arranged substantially as set forth, each being connected at one end separately to one of said contact terminals, and being connected at their opposite ends separately in opposite sides of an electric circuit, and the field 10 winding of the magnet being connected in one side of the same circuit. 15

10. An electromagnetic impulse motor comprising a magnet armature, a switch carrier and a driving member mounted to oscillate about the 20 same axis, the armature and driving member being rigidly connected together and the switch carrier being independently oscillatable, connections between the switch carrier and armature organized to drive the former positively in each 25 direction with capacity for a limited degree of lost motion, a magnet having poles embracing said armature, a spring connected to the armature tending to place the armature in a position of greater than minimum reluctance with respect to the magnetic field and a stop coacting therewith for so positioning the armature, the spring being put under increased stress by movement of the armature effected by excitation of the magnet, a spring connected to the 30 switch carrier and arranged to hold the latter at one limit of its lost motion when the armature is in the before mentioned position of reluctance, and to shift the carrier to the other limit of its lost motion when the armature is 35 displaced by magnetic impulsion, an electric switch carried by said carrier comprising a hermetically sealed tube having separated terminal contacts in one end and a movable circuit closing body, mounted on said carrier in such position that the movable body is brought against 40 said contacts when the armature is in the before named position and the switch carrier is at the first of the above named limits of its lost motion, the movable body being displaced from 45 contact when the armature and carrier are moved by magnetic action. 50

11. An electromagnetic impulse motor as set forth in claim 10 in which the switch is mounted eccentrically with respect to the carrier, whereby its movable circuit closing body is given momentum in the course of the lost motion of the carrier and the switch tube is arrested suddenly at each limit of such lost motion. 55

12. An electromagnetic impulse motor as set forth in claim 10 in which the spring for effecting the lost motion movements of the switch carrier is an electrical conductor and is electrically connected with one of said contacts in a circuit which includes the other contact and the winding of the electromagnet. 60

13. An electromagnetic motive apparatus comprising an electromagnet, an armature for said magnet rotatably mounted between the 70 poles thereof and movable from a position of relatively great reluctance with respect to the field of the magnet to and through a position of minimum reluctance when impelled by magnetic flux, two springs coupled to said armature and 75

both acting to exert torque on the armature in the same direction, tending to return the armature to the first named position after displacement therefrom, means including a one way clutch in rigid connection with said armature for transmitting motion from the armature when the latter is so actuated by said springs, and a gravity circuit closer having separated terminals each in separate electrical connection with one of said springs; the springs being in

turn in separate circuit connection with the field winding of the magnet, and the gravity circuit closer being coupled with the armature for movement thereby into position for closing the circuit between its said terminals when the armature is in and near the first named position, and to break the circuit when the armature is in the position of minimum reluctance. 5

JEAN FINK. 10
